UNITED STATES PATENT OFFICE.

JOHN E. BELL, OF BROOKLYN, NEW YORK, ASSIGNOR TO SINCLAIR REFINING COMPANY, OF CHICAGO, ILLINOIS, A CORPORATION OF MAINE.

PRESSURE STILL HEATING FURNACE.

Continuation of application Serial No. 532,482, filed January 28, 1922. This application filed April 1, 1924. Serial No. 703,340.

This invention relates to an improved method and apparatus for cracking oil, and involves an improved method of heating of oil cracking stills and improvements in cracking still heating apparatus whereby danger of overheating is avoided or minimized and a more uniform heating action is obtained.

The invention relates particularly to improvements in the heating of pressure stills for cracking hydrocarbons of higher boiling points, such as crude petroleum, gas oil and the like, to form more volatile or lighter hydrocarbons, such as those that constitute commercial gasoline or pressure distillate, and the apparatus therefor.

Among the objects of the invention are the protection of the tubes or oil heating surfaces of cracking stills from overheating or burning, the lengthening of the time of the runs between cleaning with a corresponding increase in the distillate produced, and a more uniform distribution of the heat throughout the heating chamber, and other advantages which will appear from the following description.

Pressure stills and other stills for cracking oil are heated by furnaces in which coal, gas or oil is burned, and, for economy in fuel consumption, it is desirable that the fuel be burned in the furnace with the least amount of excess air and at maximum furnace temperature. Excessive temperatures are, however, objectionable in the heating chambers of oil cracking stills. Carbon is formed during the cracking operation and tends to deposit on the inside of the tubes or heating surfaces of the still and such a layer of carbon or of heavy tar is a poor conductor of heat and insulates the surface from the oil on the inside, with the result that the temperature of the metal heat absorbing surface increases over the temperature of the oil, the amount of this increase being proportional to the thickness of the carbon deposit and to the amount of heat delivered to the external surface heated by the furnace gases. The overheating of the still or of the tubes or heating elements of a cracking still, and the resulting increased tendency of carbon formation, tend to give hot spots and involve a considerable element of

danger or hazard to life and property due to the possible bursting of a part of the heating surface which has become over-heated or burnt. In an oil cracking still the tubes or heating surfaces most exposed to the heat of the furnace and over which the heating gases first pass are the first to suffer. The danger of overheating such tubes or other heating surfaces most exposed to the heat of the furnace can be decreased by reducing the fuel consumption, but this in turn reduces the capacity of the still; while, if the still is driven hard to increase its capacity by increasing fuel consumption, the danger of overheating is greatly increased.

According to the present invention, the heating of the still is modified and regulated to avoid or greatly reduce the danger of overheating and to secure a more uniform heating action.

According to the present invention, the products of combustion from the fire box are tempered by admixture with hot gases at a lower temperature before the admixed heating gases are brought into contact with the tubes or other heating surfaces of the still, thereby reducing the temperature to which the first tubes or surfaces are subjected and the amount of heat absorbed by them, and increasing the amount of heat absorbed by tubes or surfaces over which the gases pass before escaping from the heating chamber. This tempering of the products of combustion from the furnace is nevertheless effected without sacrificing either fuel economy or still capacity, and may even result in a considerable increase in still capacity.

With the ordinary furnace arrangement, such as commonly used under stills, a large proportion of the heat in the fuel passes directly from the fuel bed where solid fuel is used, or from the frame and hotter brick work when gaseous or oil fuel is used directly to the heat absorbing surfaces by radiation. It has been shown by tests that the amount of heat absorbed by the surfaces next to the fire may be and usually is 40 or 50 times as great as the average absorption of heat throughout the whole surface, and this amount of heat is principally transferred as radiant energy. It has also been

- shown that the amount of heat transferred in this way increases very rapidly with the furnace temperature, the process in general being controlled by Stefan's law for radiation which makes the total amount of radiation proportional to the fourth power of the absolute temperature of the radiant. When the furnace is arranged so that the heat absorbing surfaces are shielded from direct 5 radiation, the interposed shields and the connecting passages become secondary radiators and the total amount of heat transmitted by radiation is absorbed by the heating gases with the result that there is an actual increase 10 in the temperature of the heating gas coming in contact with the heated surface of the boiler or still, although this increase in gas temperature does not compensate for the reduction in the radiant heat.
- According to the present invention, the heat absorbing surface of the cracking still is protected from direct radiation from the furnace by the interposition of suitable passages or screens, such as a high bridge wall 15 and a vertical flue with refractory walls, or by other suitable arrangement of the fire box and heating chamber.

Also, according to the present invention, the products of combustion from the furnace 20 are diluted and tempered with a heated gas before they are passed over the oil heating surfaces. For example, I may introduce a diluting body of air or gas into the connecting flue between the furnace and heating 25 chamber at a point near the furnace. The addition of such a tempering body of hot air or gas reduces the gas temperature where the heating gases first contact with the heating surfaces of the still, and also the temperature 30 of the refractory walls. The heat absorbed by the surface or surfaces of the still with which the furnace gases first contact is thus reduced in two ways, namely, by the lower temperature of the heating gas, 35 and by a reduction in the temperature of the refractory secondary radiating surfaces.

If the diluting air or gas is not heated, the result is a reduction in efficiency such as accompanies the burning of fuel with an 40 excessive amount of cold air. According to this invention, however, the diluting air or gas admixed with the products of combustion is heated, for example, to approximately 45 the temperature of the waste heating gases leaving the heating chamber of the still. I have found that if the temperature of the diluting gas is approximately that of the waste heating gases leaving the still surface not only is there no reduction in the 50 fuel economy and in the capacity of the still, but, on the other hand, there is a slight increase in both.

This application is a continuation of my prior application filed January 28, 1922, Ser. 60 No. 532,482. In one method of operation

described in said prior application, a proportion of the hot waste heating gases at the temperature at which they leave the heating chamber of the still is drawn aside and returned for tempering the hot products 70 of combustion from the furnace. The present application relates more particularly to an improved method and apparatus in which preheated air or gas is employed as the diluting and tempering medium. 75

According to this invention, air or gas is preheated by heat interchange with the escaping heating gases from the heating chamber and the heated air or gas admixed with the furnace gases. An air heater may 80 be installed in a flue leading from the heating chamber of the still and air forced through and preheated to the proper temperature in this heater and then introduced into the furnace gases before the admixed 85 furnace gases and preheated air are brought in contact with the tubes or other heating surfaces of the still.

Where a part of the hot waste heating gases from the still are employed as the 90 heated diluent, as described in the above referred to prior application, and the same amount of fuel is burned in the furnace, a measure of the efficiency and capacity of the still can be made from the temperature and 95 weight of the waste gases. The weight of the waste gases, however, is not changed by the continuous recycling of a part of the waste gases, and experience has shown that the temperature of the waste gases escaping 100 from the still is reduced. As a result, the efficiency and capacity of the still are somewhat increased.

When preheated air or gas is used for the heated diluent, and at approximately 105 the temperature of the exit gases leaving the still, as is the case where the tempering medium is heated by heat interchange with the hot waste exit gases in a waste gas heater of sufficient proportions, the same 110 considerations apply and the efficiency and capacity of the still are slightly increased. When the waste gas heater is somewhat smaller than will heat the tempering air or gas to approximately the temperature of the waste gases, there may be a slight reduction 115 in efficiency and capacity.

The invention is of more or less general application for the heating of oil stills, and particularly of tubular oil cracking stills 120 where the oil is circulated through tubes passing through the furnace, for example, where the oil is circulated upwardly through vertical tubes or where the oil is circulated through horizontal tubes extending through 125 or arranged in the heating chamber.

In a tubular oil still the circulation of the heating gases is advantageously countercurrent, or in a general countercurrent direction, to that of the oil. Where, for example, 130

the oil is circulated upwardly or in a general upward direction through a tubular still, or through the tubular heater of a still, the gases are circulated in a general downwardly direction; and the present invention is of particular value for use with such a tubular cracking still. In such a still, the oil is heated in its upward flow and is hottest in the upper tubes or in the upper portions of the tubes. Where the high temperature products of combustion are introduced into the top of the heating chamber containing such tubes, the tubes containing the hottest oil are subjected to the greatest heat. According to the present invention, the excessive temperatures of combustion are moderated and the products of combustion are cooled before they are brought into contact with the tubes or portions of tubes containing the hottest oil. The more uniform distribution of the heating gases gives an increased heating effect in the lower tubes or in the lower portions of the tubes so that in general a more uniform heating of the oil flowing through the tubular heater is accomplished, as well as the avoiding of excessive over-heating of any portions of the tubes.

The invention will be further described in connection with an oil still such as that described and illustrated in Patent No. 1,285,200, granted to the Sinclair Refining Company, November 19, 1918, on the application of Edward W. Isom; but it will be understood that the invention is of more general application, although it is of particular value with a tubular cracking still of the character referred to in said patent.

In the accompanying drawings I have shown certain forms of apparatus embodying the invention and in which the process of the invention can be practiced, and the invention will be further described in connection therewith. It is to be understood however that these specific illustrations and description are for the purpose of exemplification and that the scope of the invention is defined in the following claims, in which I have endeavored to distinguish it from the prior art so far as known to me, without, however, relinquishing or abandoning any portion or feature thereof.

In the oil cracking stills illustrated more or less diagrammatically in the drawings, the products of combustion coming from the fire box are tempered by an admixture of hot gas or air which has been preheated by heat interchange with the hot waste heating gases leaving the heating chamber.

In the accompanying drawings,

Fig. 1 shows in longitudinal vertical section an oil heating furnace in which the gases from the fire box are tempered by means of preheated air.

Fig. 2 is a similar view of a somewhat dif-

ferent type of oil heating furnace in which the oil heating tubes are horizontal instead of vertical,

Fig. 3 is a transverse, vertical section on the line 3—3 of Fig. 2, 70

Fig. 4 is a horizontal section on the line 4—4 of Fig. 2, and

Fig. 5 a fragmentary sectional view on the vertical plane of line 5—5 of Fig. 4.

It will be understood that only the heater portion of the cracking still is shown in the accompanying drawings. In connection with an oil cracking still of the general construction illustrated in Patent 1,285,200, the bulk supply tank containing the greater portion of the charge of the pressure still is arranged away from the furnace and the oil is circulated from the bulk supply tank through the heating tubes and back to the bulk supply tank. In its broader aspects, the invention is of general application to tubular cracking stills including single pass tubular cracking stills and other stills of various types and designs.

In the accompanying drawings, corresponding parts are designated by the same reference characters.

Referring to the drawings, the oil heating furnace illustrated in Fig. 1 comprises a fire-box 1, which may be of any usual or preferred form, communicating by an elongated throat 2 with the upper end of the heating chamber 3 containing the oil heating tubes. The chamber 3 is of considerable vertical length and communicates at its lower end with a stack flue 4. The fire box is shown as equipped at 5 with a mechanical stoker and at 5^a with burners by means of which oil or gas may be used as fuel. The elongated throat 2 is separated from the heating chamber 3 by a lengthy bridge wall 6 which overhangs at its top, as at 30, into the throat of the fire-box. The purpose of the elongated throat, and of the overhanging bridge wall, is to shield the tubes in the heating chamber 3 from direct radiation from the fire box 1.

The battery of heating tubes 7 is connected at top and bottom to headers 9 and 12, respectively, both of which headers are outside the heating chamber. The tubes 7 extend through an opening 8 in the top wall of the furnace which is closed by a perforated slab 8^a of refractory material through which the tubes extend. At their lower ends, the tubes 7 extend through a slab or slabs of refractory material 10 beneath which the header 12 is located. The slabs of refractory material may rest upon collars formed on the tubes, as shown in Fig. 1, and the plates or slabs 10 may rest upon angle irons 13 at their edges. The entire battery of tubes is supported from the top header so as to be free to expand and contract with change of temperature.

The lower header 12 is connected to a

- manifold 12^a which receives oil through the pipe 12^b. The upper header is connected to a manifold 9^b which in turn connects with a pipe or pipes 11. The oil received through pipe 12^b enters the header 12, flows upwardly through the bank of tubes 7 to the upper header 9 and thence through the upper manifold and pipe 11. When the heater is employed in a system of the type shown in the Isom patent, to which reference has been made, the pipes 11 and 12^b are connected to the bulk supply tank (not shown) and preferably one or both of them is provided with means for accelerating the circulation as shown in said patent.
- The heating chamber is provided with baffles 14 and 15 which cause the hot gases to pass back and forth among the tubes of the battery a number of times before reaching the flue 4, by which they make their exit from the heating chamber. By reason of this thorough circulation about and in contact with the oil heating tubes, heat is efficiently extracted from the products of combustion before they reach the flue 4. The efficiency is further increased due to the fact that the general directions of the flow of the heating gases and of the oil are opposed so that the relatively cool oil entering at the bottom of the tubes extracts the heat from the partially cooled gases and the temperature of the oil increases until it is at the maximum in the upper pass of the furnace where it is exposed to the gases fresh from the fire-box. The oil heating tubes are, however, screened from direct radiation from the fire-box, even at their upper ends, thus preventing overheating with consequences to which reference has heretofore been made.
- In order to reduce the temperature of the hot products of combustion coming from the fire-box before they strike the oil containing tubes, I provide means for tempering the fresh products of combustion from the fire-box with preheated air at lower temperature. For this purpose I provide a vertical flue 40 communicating at its lower end with the flue 4 and at its upper end with a horizontal flue 31 leading to a stack. A battery of vertical tubes 32 is arranged in this vertical flue and communicates at its upper end with a boxing or flue 33 through which the tubes 32 are supplied with air. The lower end of this tube battery communicates through a header 35 with a horizontal flue 34 leading to a transverse flue or boxing 18 extending across the throat of the fire box. This box is formed with a longitudinal opening or openings 19 communicating with the throat of furnace. The spent gases from the bottom of the heating chamber pass up through the vertical flue 40 and the battery of air heating tubes 32 therein. The air entering the flue 33 flows countercurrent to the hot waste heating gases from the heating chamber 3^a down the tubes 32 and into the flue or flues 34 along which it flows to the outlet 34^a where it intermingles with and tempers the hot products of combustion from the fire box.
- It will be evident that the amount of hot preheated air or gas introduced into the hot

flue 34 along which it flows to the outlet or outlets 19 where it intermingles with and tempers the hot products of combustion from the fire-box.

In the oil heating furnace illustrated in Figs. 2 to 5 inclusive, the general arrangement of the furnace, including the fire box 1^a, the elongated vertical throat 2^a, and downwardly extending heating chamber 3^a with baffles 14^a and 15^a therein, is substantially like the oil heating furnace heretofore described. The oil heating tubes 7^a, however, are arranged horizontally in the heating chamber and connect series of headers 36, 36^a etc. and 37, 37^a etc., arranged respectively in openings in the opposite side walls of the heating chamber. The openings are closed outside the headers by doors 41 of suitable material. The lowermost header on the left hand side of the furnace, as shown in Fig. 3, is provided with a connection 42 to serve as an inlet for the oil, and the upper header on the same side is provided with a similar connection 43 to serve as an outlet for the oil. It will be noted that the uppermost and lowermost headers on the left hand side of the furnace, that is the headers to which the inlet and outlet are respectively connected, receive only two horizontal rows of pipes whereas the intermediate headers on the same side and all of the headers on the other side of the furnace receive four horizontal rows of pipes. This provides for a continuous circulation of the oil received through the inlet 42 back and forth across the heating chamber in its passage to the outlet 43 so that it is exposed many times in its passage through the furnace to the heat of the products of combustion circulating about the heating tubes as they pass back and forth across the tubes in passage from the top to the bottom of the heating chamber.

A stack flue 4^a communicates with a vertical flue 40 which at its upper end connects with a horizontal flue 41 returning to a stack. A battery of vertical tubes 32 is arranged in this vertical flue and communicates at its upper end with a boxing or flue 33 through which the tube battery 32 is supplied with air. The lower ends of the tubes 32 communicate through a header 35 with a horizontal flue or flues 34 leading to an outlet 34^a in front of the bridge wall. The spent gases from the bottom of the heating chamber 3^a pass up the vertical flue 40 and heat the tube battery therein. The air entering the flue 33 flows countercurrent to the hot waste heating gases from the heating chamber 3^a down the tubes 32 and into the flue or flues 34 along which it flows to the outlet 34^a where it intermingles with and tempers the hot products of combustion from the fire box.

It will be evident that the amount of hot preheated air or gas introduced into the hot

products of combustion from the fire box can be varied and the temperature of combustion gases correspondingly modified before they reach the tubes through which the oil is circulated. The temperature in the fire box may, for example, be maintained around 2400° F. and this temperature may be reduced by admixture of preheated air or gas, for example, to a temperature of about 10 2000° F. before the admixed heating gases reach the tubes. In their passage through the first pass of the heating chamber the gases may be reduced from about 2000° to 15 1300° F. at which temperature they enter the second pass, where they may be reduced to about 1000° F. The gases finally leaving the lower pass may be reduced to about 800° F. at which temperature they enter the pre-heater for the tempering air or gas. The 20 regulation of the introduction of the hot tempering diluent is independent of the rate of combustion in the fire box, and, with a sufficient introduction of the tempering medium, the rate of combustion may be somewhat increased without objectionable overheating of the surfaces of the cracking still by the admixed heating gases.

It will thus be seen that the present invention provides for the reduction of the 30 furnace temperature of the heating gases at the point where they first come in contact with the surfaces of the cracking still and that this reduction of temperature permits a milder condition of heat absorption in 35 these tubes with resulting less coke formation, while the reduction of temperature in the furnace by recirculation of gases protects the brick work and prevents slagging of the same. The fast velocity of gases past 40 the tubes tends to prevent the deposit of furnace slag and dust upon the tubes with resulting impairing of vision of the tubes and heat conductivity.

It will further be seen that these and 45 other advantages are obtained without sacrifice of the efficiency of the furnace but that the efficiency is somewhat increased, as well as giving a more uniform application of heat to the oil heating surfaces. As a 50 result, the life of the heating tubes or elements is greatly increased, while the danger of injury from overheating and burning is greatly reduced, and the apparatus can be operated for longer periods of time without 55 requiring shutting down for cleaning. The furnace linings are also prolonged because of the lower temperature of the gases which are brought in contact therewith.

While the invention is of more or less 60 general application to oil stills, and particularly to tubular stills, it is of special value in oil cracking stills operated at a high pressure where there is tendency for carbon deposits to form on the heating surfaces and where the failure of any part of

the still is accompanied with great hazard to life and property. In a tubular oil cracking still the invention makes the heating of the tubes more uniform, increases the efficiency of heat transfer, and decreases or removes altogether the danger of overheating; while nevertheless taking full advantage of the heat of the furnace gases utilized in heating the still. 70

I claim:

1. An oil cracking still, having a heating chamber with oil heating surfaces therein, a fire box communicating with said chamber, means for preheating air with the hot gases leaving the heating chamber, and means for 80 tempering the hot products of combustion from the fire box with the preheated air before the admixed air and combustion gases enter the heating chamber. 75

2. An oil cracking still, having a heating chamber with oil heating surfaces therein, a fire box communicating with said chamber, a stack flue communicating with said chamber, means in said stack flue for preheating air and means for tempering the hot products of combustion from the furnace with 90 the preheated air before the admixed gases enter the heating chamber. 85

3. A tubular oil cracking still having a heating chamber with oil heating tubes 95 therein, a fire box communicating with said chamber, means for preventing direct radiation from the fire box against the tubes, means for preheating air with the hot gases leaving the heating chamber, and means for 100 tempering the hot products of combustion from the fire box with the preheated air before the admixed gases enter the heating chamber. 100

4. A tubular oil cracking still having a 105 heating chamber with oil heating tubes therein, a fire box communicating with said chamber, a stack flue communicating with said chamber, means in said stack flue for preheating air and means for tempering the 110 hot products of combustion from the fire box with the preheated air before the admixed gases enter the heating chamber. 110

5. An oil cracking still having a heating chamber with oil heating surfaces therein, a fire box communicating with said chamber, means for preventing direct radiation from the fire box against the oil heating surfaces, means for preheating air with the hot gases leaving the heating chamber, and means for 115 tempering the hot products of combustion from the fire box with the preheated air before the admixed gases enter the heating chamber. 115

6. The improvement in the heating of oil cracking stills in which oil is heated to the cracking temperature by hot products of combustion from a fire box passing externally over the oil heating surfaces of the still, which comprises preheating air by heat

exchange with hot waste heating gases which have passed over the heating surfaces, admixing the preheated air with the hot products of combustion from the fire box, and 5 passing the resulting admixed heating gases over the oil heating surfaces.

7. The improvement in the heating of oil cracking stills in which oil is heated to the cracking temperature by hot products of 10 combustion from the fire box passing externally over the oil heating surfaces of the still which comprises preheating air to a temperature approximately equal to the temperature of the hot waste heating gases leaving the heating surfaces and passing the preheated air in admixture with the hot products of combustion from the fire box over the heating surfaces.
8. The improvement in the heating of oil cracking stills in which oil is heated to the cracking temperature by hot products of 15 combustion from a fire box passing externally over the oil heating surfaces of the still, which comprises preheating air by heat exchange with hot waste heating gases 20
- 25

which have passed over the heating surfaces, admixing the preheated air with the hot products of combustion from the fire box before passing the admixed heating gases over the heating surfaces and passing the 30 resulting admixed heating gases over the oil heating surfaces, and also preventing direct radiation from the fire box to the oil heating surfaces.

9. The improvement in the heating of 35 tubular oil cracking stills in which oil is heated to the cracking temperature by hot products of combustion from a fire box passing externally over the oil heating tubes, which comprises preheating air by heat exchange with hot waste heating gases which have passed over the heating tubes, admixing the preheated air with the hot products of combustion from the fire box, and passing the resulting admixed heating gases over the oil heating tubes. 40

In testimony whereof I affix my signature.

JOHN E. BELL.
